SERVING TRAY

Milton F. Klein, Glens Falls, N. Y., assignor to
Jaxton Manufacturing Corporation, Glens
Falls, N. Y., a corporation of New York

Application February 17, 1953, Serial No. 23,655

Term of patent 7 years

(Cl. D44—10)

To all whom it may concern:

Be it known that I, Milton F. Klein, a citizen of the United States, residing at Glens Falls, county of Warren, State of New York, have invented a new, original, and ornamental Design for a Serving Tray, of which the following is a specification, reference being had to the accompanying drawing forming a part hereof.

Fig. 1 is a plan view of the serving tray embodying my new design;

Fig. 2 is a view in side elevation of the serving tray;

Fig. 3 is a vertical longitudinal sectional view of the serving tray taken on line 3—3 of Fig. 1; and

Fig. 4 is an end view of the tray as it would appear from either end in Fig. 1.

I claim:

The ornamental design for a serving tray, as shown.

MILTON F. KLEIN.
